UNITED STATES PATENT OFFICE.

JOHN FRANCIS HARWOOD, OF NEW YORK, N. Y.

PERFUME-VENDING MACHINE.

Application filed March 5, 1925. Serial No. 13,032.

This invention relates to vending machines, and more particularly to coin controlled machines for dispensing liquids and the like.

5 A prime object of my present invention comprehends the provision of an improved perfume vending machine of the type wherein a predetermined charge or quantity of perfume may be dispensed in the form of a spray for application to the person of the operator or to an article of apparel. In a preferred form of known machines of this type, an atomizer embodying a compressible bulb is operated by a bulb compressing member when a coin of suitable denomination is deposited into the machine; and in accordance with a preferred form of construction, the coin serves as a means for connecting the bulb compressing member with a manually 10 manipulable device, so that when the proper coin is deposited into the machine, manipulation of the device will compress the bulb to operate the atomizer.

In vending machines of this type, it is 15 highly desirable that the construction be such as to assure the user or operator that a full and complete charge of perfume spray will be dispensed when a coin of proper denomination is deposited into the machine and such as to prevent either more or less of a predetermined charge to be ejected such as might be obtained by a pumping operation of the operating mechanism. It is further desirable to construct and inter-relate the 20 parts of the machine so as to reduce the number of parts to a minimum and organize the same in accordance with a simple law of combination, this to permit assured operation and to eliminate the necessity of frequent repair or replacement of parts. A further desideratum in a machine of this type centers about the provision of mechanism which will permit the machines to be 25 readily accessible for refilling purposes, while maintaining the coin-controlled apparatus and the coin receptacle in locked condition. The production of a perfume vending machine in which these desiderata are achieved to a high degree in an efficient manner is a principal object of the present invention.

To the accomplishment of the foregoing and such other objects as will hereinafter appear, my invention consists in the elements and their relation one to the other, as

hereinafter more particularly described and sought to be defined in the claims; reference being had to the accompanying drawings which show a preferred embodiment of my invention, and in which:

Fig. 1 is a perspective view of the perfume vending machine embodying the principles of my invention;

Fig. 2 is a side elevational view thereof taken in cross-section in the plane of the line 2-2 of Fig. 1, and showing the same on an enlarged scale;

Fig. 3 is a view taken in cross-section in the plane of the line 3-3 of Fig. 2;

Fig. 4 is a front elevational view with the front door removed and with parts broken away.

Fig. 5 is a view similar to Fig. 2 but showing the parts in a different operative position.

Referring now more in detail to the drawings, the vending machine comprises a dispensing device of the atomizer type generally designated as A mounted on and carried by a frame generally designated as B, 80 which frame houses a coin-controlled mechanism generally designated as C, the frame being enclosed in a housing or casing generally designated as D.

The casing D which houses all of the operating parts of the machine may be made in any preferred form embodying an ornamental configuration, said casing preferably including a box-like casing section d, having top and bottom walls 10 and 11, the side walls 12 and 13, a rear wall 14 and a removable front wall 15, the top wall 10 including a slotted element 16 for receiving a coin of proper denomination and the front removable wall 15 including a locking device 17 openable for removing the front wall, an opening 18 through which the spray nozzle of the vending machine projects and an opening 19 through which extends the manually manipulable part of the operating mechanism, as will be described more fully hereinafter. The casing D also includes an upright section d' preferably made integral with the rear wall 14 of the casing section and which upright desirably forms a frame 100 for a mirror or reflecting device 20. For enhancing the appearance of the vending machine and for instructive purposes, the same may be provided with an instruction sheet or plate 21 arranged inclinedly in a 110

triangular shaped frame 22 connected to the casing sections, as is clearly shown in Figs. 1 and 2 of the drawings.

The supporting frame B for the operating mechanism preferably comprises a unitary casting in the form of a housing constructed so that the frame forms a housing for the operating parts of the mechanism and a receptacle for the coins deposited therein and a support for the atomizer structure A, with the construction such that when the front closure wall 15 of the casing D is removed access may be had to the parts of the atomizer for refilling purposes while the receptacle is maintained in locked condition to permit only duly authorized agents to open the latter. Accordingly the frame B comprises a mechanism housing section 23 open at the top and at one side thereof, as is clearly shown in Figs. 3 and 4 of the drawings, and a coin depository section 24 integral therewith, the coin depository section having a front closure 25 locked by means of a lock mechanism 26. The casting frame B is secured to the casing D by means of securing elements 27, 27 which secures the apertured ears 28, 28 integrally with the casting frame to suitable bracket portions 29, 29 provided in the casing, and in order to prevent removal of the casting frame except by authorized agents the said frame is additionally secured to the casing by means of a bolt 30 fixed interiorly to the rear wall 14 of the casing and connected to the rear wall of the frame casting by means of a nut 31 threadedly received by the inner end of the bolt 30 within the depository section 24 of the casting. With this construction it will be seen that only when the front closure 25 of the depository section is opened may the casting frame be detached for removal from the casing. Preferably the casting frame B forms the locking support for the casing closure 15, the lock 17 being provided with the lock bolt 17' which cooperates with an opening in the casting frame as is clearly shown in Fig. 3 of the drawings.

For suitably supporting the parts of the atomizer on the exterior walls of the casting frame B, the frame includes a yoke bracket 32 preferably formed integrally with the casting, the said yoke bracket having registering bushings 33 and 34 receiving opposite ends of a compression bulb 35, which compression bulb is sealed at its lower end and open only at its upper end for purposes referred to hereinafter, the said yoke bracket further including a bulb engaging convexed section 36 against which the bulb 35 is compressed. For supporting a bottle 37 of the atomizer, a suitable saddle frame 38 which may also be formed integrally with the casting is provided and preferably this frame is so designed as to support the bottle 37 in inclined position, as is clearly

shown in Fig. 2 of the drawings. The atomizer further includes the usual tube 38' connecting the bulb 35 with the bottle 37 and the discharge duct 39, which terminates in the spray nozzle 40, which spray nozzle projects through the opening 18 of the casing closure 15.

The coin-controlled operating mechanism C comprises a bulb compressing member c' which cooperates with the bulb 35 of the atomizer and is held in normally retracted position, as shown in Fig. 2 of the drawings, by the expansive force of the bulb, a movable coin receiving device c² which is normally unconnected to the bulb compressing member c' but which is adapted to be connected thereto by the medium of a coin deposited in the machine, and an operating means generally designated as c³ which is connected to the coin receiving device c² for operating the latter.

In carrying out some of the desired objects of the present invention as heretofore stated, the parts of the coin-controlled mechanism are designed, constructed and inter-related to assure the user or operator that a full and complete charge of perfume spray will be dispensed and to prevent more than a predetermined charge to be ejected such as might be obtained by a pumping operation of the mechanism. Accordingly the parts of the operating mechanism are organized to permit the desired operation only when the parts are in a normal or fully retracted condition and to permit operation provided that the user follows out the intended operating cycle and does not attempt to improperly employ the machine.

The bulb compressing member preferably comprises a plunger 41 slidably movable in an extended bearing 42 formed integrally with the casting frame B, the said plunger being provided with a concave bulb engaging disc section 43, the plunger being preferably restrained against rotation by means of adjustable pin 44 held in the bearing 42 and keyed in the way 45 in the plunger. (See Fig. 2.) The plunger 41 is also provided with a block 46 which has a coin receiving opening or slot 47. Cooperating with the plunger 41 and for the purpose of positioning a coin in the slot 47, as will become clear hereinafter, I provide positioning means in the form of a plurality of pins 48, 48 fixed to the front wall of the casting frame B, said pins being received by apertures 49, 49 in the block 46, the construction being such that when the plunger is in its normal or retracted position the pins 48, 48 intersect the coin slot 47 forming means for positioning a coin received by the slot and for holding the coin in received position.

The movable coin receiving device c² comprises preferably a pivotally mounted coin

chute 50 the upper end of which registers with the coin slot 16 when in retracted position, the said coin chute being hingedly connected by means of the hinge pins 51, 51 to bracket bearings 52 in the side walls of the frame casting B. The pivoted chute is normally unconnected with the bulb operating plunger 41 but is adapted to be connected thereto when a coin of proper denomination is inserted in the machine. When a coin such as 53 is inserted in the chute with the parts as shown in Fig. 2 of the drawings, the coin will drop into position in the slot block 46 and on to the pins 47, the chute being then in registration with the slot 47 of the block. With the coin so positioned the pivoted chute is connected to for operating the bulb compressing plunger when the chute is moved from the position shown in Fig. 2 to that shown in Fig. 5.

For the purpose of assuring that a full and complete spray charge is dispensed, I provide means for preventing the proper positioning of the coin except when the chute is in a fully retracted condition. To this end there is provided a stud or pin bolt 54 fixed to a bracket portion 55 of the casting frame, which stud bolt projects through an extended slit 56 in the chute and is of a length such that a coin deposited in the chute will clear the same when the chute is in fully retracted position, as shown in Fig. 2, and will be obstructed or held by the same when the chute is in non-retracted position as shown in Fig. 5. The parts moreover cooperate so that if a coin is deposited with the parts in the position shown in Fig. 5 the parts not only must be moved but may be moved to normal position before effective operation is permitted.

For the purpose of preventing improper activity or operation of the mechanism, the pivoted chute c^2 and plunger c' cooperate to permit a continued cycle of operation and to prevent a breaking of the cycle as when the operator may desire to pump or successively actuate the atomizer mechanism. To these ends the chute 50 is provided at a region adjacent the slotted block with a roller 57 which is positioned to engage and ride on the coin 53 and to bind the same in the slot block 46 of the bulb compressing plunger, as will be clearly apparent from a consideration of Figs. 2 and 5 of the drawings. As will be further apparent from Fig. 5 of the drawings, when the chute is moved from its normal position the block 46 is withdrawn from the pins 48 and the coin is thus held in position only by the binding action of the roller thereagainst. Still referring to Fig. 5 of the drawings, it will be seen that when the chute is moved beyond a predetermined position it will become disconnected from the coin 53 and the coin will then be free to drop through the slot

47 and into the coin depository 24, the plunger 41 being then free to be returned to its normal retracted position which is accomplished by the expansive force of the bulb 35. By providing the roller 57 riding over the coin 53 the point of disconnection between the parts and therefore the period of discharging operation of the atomizer may be predetermined to a nicety. It will further be evident that should the operator desire to pump or repeatedly actuate the atomizer, as by a return movement of the chute, the coin 53 will be released and will drop into the receptacle.

The operating means c^2 for the coin chute preferably comprises a slide rod 58 slidably movable in an extended bearing 59 formed in the casting frame and projecting through the opening 19 of the casing D, the said slide rod being provided with a finger or hand knob 60. The slide rod 58 is provided with a link 61 at its inner end, which link embraces a downwardly extending portion 62 forming part of the chute c^2 . It will be apparent that with this construction the parts are controlled by the sliding operation of slide rod 58. If it is desired to prevent return movement of the chute except after a completed stroke of the slide rod the latter may be provided with a series of ratchet teeth 63 with which cooperates a weighted pawl 64, the slide rod being provided at opposite ends with enlarged recesses 65 and 66, these parts functioning to prevent return movement of the operating rod except after a full stroke of the rod has been made as when the tooth of the pawl 64 is free to move into the enlarged recess 66. Normally the pawl 64 is in vertical position, the tooth thereof being free to move in the enlarged recess 65, as is clearly shown in Fig. 2 of the drawings. To limit the retracted or return movement of the chute, there is preferably provided a stop pin or stud 67 fixedly carried by the front wall of the casting frame B.

The use, operation and many advantages of my improved perfume vending machine will in the main be fully apparent from the above detailed description thereof. It will be seen that the operating construction embodies only three operating elements, which are of simple design and which cooperate without the employment of springs or the like, a rugged, durable and easily operable structure being thereby afforded. It will be seen that the normal position of the plunger is controlled by the expansive force of the bulb and that the normal retracted position of the chute and slide rod is manually effected, the construction being such that the parts must be moved manually to the retracted position before an operation is permissible. It will be further evident that by organizing the parts in the manner shown

and described, embodying a simple law of organization or combination, an efficient and serviceable structure is produced which is capable of being manufactured and sold at low cost. In operation the user or consumer is assured at all times of a predetermined and "full measure" charge and the user is compelled to operate the machine in a simple and in the proper manner. By employing a bulb such as 35 sealed at its lower end and open only at its upper end, the perfume liquid can not be siphoned from the bottle outside of the casing or housing, and the back suction of the bulb prevents drip and sediment collecting at the spray nozzle. Moreover, with this construction sediment and drip is drawn back into the bulb, maintaining the spray apparatus in clean and workable condition.

20 While I have shown my vending machine in the preferred construction, it will be apparent that numerous changes may be made in the construction of the parts and the inter-relation of the same without departing 25 from the spirit of the invention defined in the following claims.

I claim:

1. A vending machine for dispensing liquid perfumes or the like, comprising a casing having a coin opening therein, a yieldable operating member, a pivoted coin chute located entirely within the casing and adapted to be moved into and out of alignment with the coin opening and normally unconnected to the operating member, mechanism connected to the lower portion of the chute for moving the same and means whereby a coin deposited in the chute forms a connection between the chute and the operating member, the chute and the said member being associated so that arcuate movement of the chute beyond a predetermined position will disconnect the chute from the member permitting the coin to drop and the member to return to its retracted normal position.

2. A vending machine for dispensing liquid perfumes or the like, comprising a slideable plunger, a pivoted coin chute normally unconnected to the plunger, a sliding rod linked to the lower end of the chute for moving the same and means whereby a coin deposited in the chute forms a connection between the chute and the said plunger, the chute and the said plunger being associated so that arcuate movement of the chute beyond a predetermined position will disconnect the chute from the deposited coin permitting the latter to drop and the plunger to return to its retracted normal position.

3. A vending machine for dispensing liquid perfumes or the like, comprising a yieldable operating member, a pivoted vertically swinging coin chute normally unconnected to the operating member, a horizontally slid-

able rod connected to the chute for moving the same and means whereby a coin deposited in the chute forms a connection between the chute and the operating member.

4. A vending machine for dispensing liquid perfumes or the like, comprising a yieldable operating member, said member having a coin receiving slot, a pivoted coin chute normally unconnected to the operating member, and a horizontally slideable rod connected to the lower portion of the chute for moving the same, said member and chute being associated so that when both are in fully retracted position the chute registers with the slot in the member whereby a coin deposited in the chute will form a connection between the chute and the operating member, the chute and the said member being also associated so that arcuate movement of the chute beyond a predetermined position will disconnect the chute from the deposited coin permitting the latter to drop and the member to return to its retracted normal position.

5. Coin controlled mechanism for a vending machine comprising an operating member, a pivoted coin chute normally unconnected to the operating member, mechanism linked to the lower end of the chute for moving the same and means whereby a coin deposited in the chute forms a connection between the chute and the operating member, the chute and the said member being associated so that arcuate movement of the chute beyond a predetermined position will disconnect the chute from the deposited coin permitting the latter to drop and the member to return to a normal position.

6. Coin controlled mechanism for a vending machine comprising a slideable plunger member, a pivoted vertically swinging coin chute normally unconnected to the said member, a horizontally disposed slide rod connected to the lower end of the chute for moving the same and means whereby a coin deposited in the chute forms a connection between the chute and the plunger member, the chute and the said member being associated so that arcuate movement of the chute beyond a predetermined position will disconnect the chute from the deposited coin permitting the latter to drop and the member to return to a normal position.

7. Coin controlled mechanism for a vending machine comprising an operating member having a coin receiving slot, a pivoted coin chute normally unconnected to the operating member, and a slide rod connected to the lower portion of the chute for moving the same, said member and chute being associated so that when both are in fully retracted position the chute registers with the slot in the member whereby a coin deposited in the chute forms a connection between the chute and the operating member, the chute and the said member being further asso-

ciated so that arcuate movement of the chute beyond a predetermined position will disconnect the chute from the deposited coin permitting the latter to drop and the member to return to a normal position.

8. Coin controlled mechanism for a vending machine comprising an operating member having a coin slot, a pivoted coin chute normally unconnected to the operating member, said coin chute being adapted to register with the slot in said member and being provided with a roller adjacent said slot and mechanism connected to the chute for moving the same.

15 9. Coin controlled mechanism for a vending machine comprising an operating member having a coin receiving slot, a pivoted coin chute normally unconnected to the operating member, said coin chute being adapted to register with the slot in said member and being provided with a roller adjacent said slot, said roller being adapted to press against a coin deposited in the slot to temporarily hold the coin in such slot, and mechanism connected to the chute for moving the same, the construction being such that when a coin is deposited in the chute it forms a connection between the chute and the operating member and is held between said roller and the walls in said slot, the chute and the said member being associated so that arcuate movement of the chute beyond a predetermined position will disconnect the chute from the deposited coin permitting the latter to drop and the member to return to a normal position.

10 10. Coin controlled mechanism for a vending machine comprising an operating member having a coin receiving slot, a movable coin receiving device normally unconnected to the operating member, said coin receiving device being adapted to register with the slot in said member and being provided with a roller adjacent said slot, said roller being adapted to press against a coin deposited in the slot to temporarily hold the coin in such slot, and mechanism connected to the device for moving the same, the construction being such that when a coin is deposited in the device it forms a connection between the same and the operating member and is held between said roller and the walls of the slot, the said device and member being associated so that movement of the device beyond a predetermined position will effect disconnection of the said device from the deposited coin permitting the latter to drop and the oper-

ating member to return to a normal position.

11. Coin controlled mechanism for a vending machine comprising an operating member having a coin receiving slot, a movable coin receiving device normally unconnected to the operating member, said coin receiving device being adapted to register with the slot in said member when both are in fully retracted position and being provided with a roller adjacent said slot, said roller being adapted to press against a coin in the slot to temporarily hold the coin in such slot, means for preventing the coin from moving into position between the device and the member when said device is not in its retracted position and mechanism connected to the said device for moving the same.

12. Coin controlled mechanism for a vending machine comprising a frame, a slidable plunger having a coin receiving slot, pins carried by said frame and associated with the slot in the plunger to form a coin positioning device therefor, movement of said plunger being effective for removing a coin from said positioning pins, a pivoted chute normally unconnected to the plunger, the said chute being adapted to register with the said slot in the plunger, a roller carried by the chute adjacent the slot, said roller being adapted to press against a coin in the slot to temporarily hold the coin in such slot in the plunger and mechanism connected to the chute for moving the same.

13. Coin controlled mechanism for a vending machine comprising a frame, a slidable plunger having a coin receiving slot, pins carried by said frame and associated with the slot in the plunger to form a coin positioning device therefor, movement of said plunger being effective for removing a coin from said positioning pins, a pivoted chute normally unconnected to the plunger, the said chute being adapted to register with the said slot in the plunger, a roller carried by the chute adjacent the slot in the plunger, said roller being adapted to press against a coin in the slot to temporarily hold such coin in such slot, mechanism connected to the chute for moving the same and means for preventing movement of a coin into cooperation between the chute and the slot when the chute is not in its fully retracted position.

Signed at Miami in the county of Dade and State of Florida this 10th day of February, A. D. 1925.

JOHN FRANCIS HARWOOD.
